BARBER CHAIR OR SIMILAR ARTICLE

John A. Dlouhy, Oak Park, Ill., assignor to Emil J. Paidar Company, Chicago, Ill., a corporation of Illinois

Filed Feb. 17, 1961, Ser. No. 63,971

Term of patent 14 years

(Cl. D15—3)

FIGURE 1 is a side elevational view of a barber chair or similar article embodying my new design;

The design is characterized by the short seat and backrest cushions in combination with the foot support and the specifically configured base, all as shown.

The portions of the back of the chair not shown are substantially plain.

I claim:

The ornamental design for a barber chair or similar article, as shown and described.
